UNITED STATES PATENT OFFICE

CARROLL M. BREED, OF YPSILANTI, MICHIGAN

WICK OIL BURNER

Application filed August 20, 1928. Serial No. 300,893.

This invention relates to oil burners and has particular reference to an oil burner of the wick type.

An object of this invention is to provide an oil burner having a novel form of wick tube and having means particularly adapted for effecting a desired deflection of air currents. A further object of this invention is to provide an oil burner having a flame spreader of novel construction adapted to effect a desired deflection and distribution of air currents. A still further object of this invention is to provide a novel construction of flame spreader which will possess a minimum number of parts and which will therefore be capable of economical manufacture and speedy assembly.

Other objects and advantages of this invention will become more apparent as the following description proceeds particularly when reference is had to the accompanying drawings wherein:

Figure 1 is a fragmentary elevational view of the body portion of an oil burner constructed in accordance with the teachings of this invention;

Figure 2 is a vertical sectional view through an oil burner embodying the invention;

Figure 3 is a top plan view of the structure shown in Figure 1;

Figure 4 is a horizontal sectional view taken substantially on the line 4-4 of Figure 2;

Figure 5 is a vertical sectional view through a slightly modified form of construction;

Figure 6 is a horizontal sectional view taken substantially on the line 6-6 of Figure 5;

Figure 7 is a fragmentary elevational view of a slightly modified form of construction;

Figure 8 is a vertical sectional view through the construction shown in Figure 7;

Figure 9 is an elevational view of the flame spreader used in connection with the construction shown in Figure 7; and

Figure 10 is a horizontal sectional view

of the wick tube in the form shown in Figure 4, taken substantially on the line 10-10 of Figure 8.

In the drawings wherein like reference characters designate corresponding parts throughout all views, there is illustrated an oil burner having the casing 15 and the wick tube designated generally by the reference character 16. The wick tube includes the inner cylindrical wall 17 and the outer wall 18 having the reversely bent lower edge 19 adapted to clamp a suitable wick 20. For raising and lowering the wick, there is provided suitable actuating mechanism which may, as illustrated, include the operating shaft 21 for driving a pinion 22 engageable with a rack 23 formed on the wall 18 of the wick tube.

Arranged within the wick tube 16 and secured to the inner periphery thereof as at 25, is an apertured plate 26 adapted to support a flame spreader designated generally by the reference character 27. The flame spreader 27 is formed of two sections consisting of a cup-shaped body portion 28 and a cap portion 29.

It forms a feature of this invention to simplify the production of the flame spreader 27 and accordingly the body portion 28 may be formed of a single stamping having imperforate side walls 30 and a bottom wall 31. The bottom wall 31 may be provided with the cut out portions 32 to form a spider, apertured as at 33 for a purpose hereinafter to be more fully described. The side walls 30 may also be provided at their upper edge with the flange 34 adapted to overlie the upper edge of the wick 20. The cap 29 is provided on its lower edge with a plurality of tongues 35 engageable in suitable slots 36 in the flange 34, these tongues being bent as shown in Figure 2 for locking the cap to the body of the flame spreader.

For rigidly clamping the flame spreader 27 to the supporting plate 26, there may be provided a suitable pin 36 extending at one end through the aperture 33 in the bottom 31 of the flame spreader and through an opening 37 formed in the plate 26. The other end of the pin 36 may extend through an opening 38 formed in the cap member

29, and the pin may be locked in position by suitable fastening members such as the nuts 39. It will thus be seen that the flame spreader will be rigidly secured to the supporting plate 26 and that the complete flame spreader may be readily formed from two easily produced stampings.

It forms a feature of this invention to effect a deflection of the air passing upwardly through the body of the flame spreader by the cap 29. Accordingly the cap 29 is provided with the angularly arranged annular wall 40 provided with a plurality of laterally directed apertures 41. Further the cap 29 is provided with the concave central portion 42 adapted to deflect air, passing upwardly through the body portion of the flame spreader, outwardly through the apertures 41. Thus a portion of the air passing upwardly through the body portion 28 of the flame spreader is deflected laterally by the concave portion 42 of the cap 29 and is discharged through the sides of the cap 29 and at an angle to the axis of the oil burner. This air passes laterally outwardly and upwardly above the flange 34 of the body member which overhangs the edge of the wick 20 and is thus prevented from mixing with the flame 44 for a considerable distance above the edge of the wick 20. Thus the flame 44 will not be broken and a higher, hotter, and steadier flame will be produced. The cap 29 is also provided with the openings 45 whereby part of the air passing through the body of the flame spreader will be mixed with the flame at a still higher level.

A further feature of this construction is to provide means carried by the wick tube 16 for deflecting air passing upwardly through the wick tube, inwardly away from the wick. Accordingly the wick tube is provided at its upper edge with the integral radially inwardly extending flange 50 terminating at a point spaced slightly from the outer periphery of the upper portion of the body portion 28 of the flame spreader. Thus air passing upwardly through the wick tube 16 will follow the course indicated by the arrows in Figure 2 being deflected inwardly adjacent the top of the wick tube and then outwardly immediately below the flange 35 of the body member 28. Thus a restricted amount of air will be fed to the flame 44 at this point whereby the flame will be prevented from breaking while receiving sufficient oxygen to prevent smoking. Further by virtue of the arrangement and location of the flange 50 the body portion 28 of the flame spreader may be spaced a considerable distance from the inner periphery of the wick tube 16, thus permitting cooling air to come in a more direct contact with the inner periphery of the wick tube to cool the same. This cooling of the wick tube in-

creases the life thereof with a subsequent saving in the expense of renewals.

The invention further contemplates the provision of a novel means for controlling the supply of air to the outer side of the flame 44. Accordingly as illustrated in Figures 1 and 2, the casing 15 is provided adjacent its upper edge with a flange 55 adapted to form a support for a burner collar 56, the latter being provided at spaced points on its inner periphery with the lugs 57 adapted to seat on the flange 55. As clearly illustrated in Figure 2 of the drawing the upper edge 58 of the burner collar 56 extends to a point slightly above the upper edge of the wick 20. Supported on the burner collar 56 is a drum 59, this drum being reversely bent adjacent its lower edge to engage a shoulder 60 formed on the outer periphery of the burner collar 56. A flange 61 carried by the lower edge of the drum 59 is extended upwardly to a point above the top 58 of the burner collar 56 and terminates adjacent the outer edge of the flange 34 of the body 28. The drum 59 is provided with the apertures 62 through which air is adapted to pass upwardly to mix with the flame 44. The air being confined by flange 61 of the drum 59 is prevented from mixing with the flame 44 until it reaches a point above the upper edge 58 of burner collar 56 as will be readily apparent by reference to Figure 2 of the drawings. Thus, this air is kept away from the outside of the burner collar and is not mixed with the flame until it has reached a point spaced substantially from the upper edge of the wick 20, thus facilitating a steadier burning of the flame.

From the above it is believed that the operation of this form of construction will be readily apparent. Air passing upwardly through the wick tube 16 will be divided by the body portion of the flame spreader 27, some of the air passing between the outer periphery of the flame spreader and the inner periphery of the wick tube. This air will be deflected inwardly by the flange 50 and then outwardly by the flame spreader to mix with the flame 44 at a point adjacent the upper edge of the wick 20. Part of the air passing upwardly through the interior of the flame spreader will be deflected laterally by the concave portion 42 of the cap 29 and will be discharged through the angularly laterally directed openings 41 to mix with the flame 44 at a point above the flange 43.

Further air passing upwardly around the outside of the wick tube will pass through the openings 62 and will be mixed with the flame 44 at a point substantially opposite the point of mixture with the flame of the air passing through the openings 41. Thus the currents of air passing through the openings 41 and openings 62 will counteract each other to effect a steady burning of the flame above the wick 20.

In Figures 5 and 6 a slightly modified form of construction is disclosed wherein the flange 50^a of the wick tube 16^a is provided with a limited number of openings 70. These openings permit a small quantity of the air passing upwardly between the inner periphery of the wick tube and the outer periphery of the flame spreader to pass directly upwardly into engagement with the flange 34^a from which it is deflected downwardly to mix with the flame 44^a. Thus the flame 44^a is supplied with an additional current of air directed at a slight angle to the current which is deflected inwardly by the flange 50 into engagement with the outer periphery of the body portion 28^a of the flame spreader. In this manner the flame is supplied with more oxygen adjacent its base and a bluer flame is produced.

In Figures 7 to 10 inclusive, a still further modification is disclosed wherein the flange 50 is eliminated from the wick tube. In this form of construction the reference character 16^b designates the wick tube and 27^b designates the flame spreader. The flame spreader 27^b is provided with the cap 29^b similar to the cap 29 and is provided with the imperforate body portion 70. This body portion 70 may be a cylindrical member secured to the cap 29^b as by the tongues 71 and may be provided adjacent its lower edge with the cam slot 72 and shoulder 73 whereby it may be locked in engagement with a cross member 74 secured to the inner periphery of the wick tube 16^b. In this form of construction, the flange 34^b similar to the flange 34 is carried by the cap member.

In order to effect a proper deflection of the air currents passing upwardly through the wick tube 16^b without, however, forming a flange integral with the upper edge of the wick tube 16^b there is provided an annular member 75 provided at its lower edge with the radially outwardly extending flange 76 adapted to seat upon a flange 77 formed on the inner periphery of the wick tube 16^b. For securing the annular member 75 to the body 70 of the flame spreader 27^b, there are provided the sheet metal V-shaped members 78 secured as at 79 to the inner periphery of the annular member 75. The lower edges of the members 78 are provided with the tongues 80 adapted to be secured to the flange 81 of a collar 82 secured to the outer periphery of the body portion 70. Thus the annular member 75 is supported in spaced relation to the inner periphery of the wick tube 16^b and the outer periphery of the body portion 70 of the flame spreader 27^b.

Secured to the upper edge of the annular member 75 is a flange 85 adapted to extend downwardly to a point adjacent the upper edge of the wick tube 16^b. The flange 76 is provided with a series of openings 86 while the annular member 75 is provided with a se-

ries of restricted openings 87. Thus air passing upwardly through the wick tube 16^b may pass upwardly through the openings 86 to the space between the annular member 75 and the inner periphery of the wick tube 16^b. This air will be mixed with the flame 44^b at a point immediately above the upper edge of the wick 23^b. Further, air may pass upwardly around the collar 81 and between the outer periphery of the body portion 70 and the inner periphery of the annular member 75 to engage the flange 34^b and be deflected downwardly to mix with the flame 44^b at a point spaced slightly above the upper edge of the wick 23^b. Further, air passing upwardly through the body portion 70 of the flame spreader will be deflected by the concave portion 42^b of the cap 29^b of the flame spreader 27^b and will be deflected outwardly through the openings 41^b to mix with the flame in the same manner as in the first described form of construction.

From the above it will be apparent that in each of the forms which my inventive idea may assume, air will be supplied to the flame at a plurality of levels. Thus some of the air passing up through the interior of the wick tube will be deflected outwardly to a point adjacent the very base of the flame. Further, some of the air passing up through the interior of the wick tube will pass through the body of the flame spreader and part of this air will be deflected through the openings 41 to be mixed with the flame at a point slightly above the base thereof. The remainder of the air passing up through the body portion of the flame spreader will pass through the openings 45 and will be mixed with the flame at a still higher level. Further, a certain amount of air will be supplied to the outer side of the flame at a level substantially opposite the level at which the air passing through the openings 41, is supplied to the inner side of the flame.

While several forms of the invention have been described with considerable detail, it is to be clearly understood that the description is for the purposes of illustration only. The right is, therefore, reserved to make such changes in the details of construction and arrangement of parts as will fall within the purview of the attached claims.

What I claim as my invention is:

1. In an oil burner, a wick tube, a burner collar surrounding the tube in spaced relation thereto to form a passage for air and projecting above the tube to deflect the air passing through said passage into contact with the flame at a point spaced a substantial distance above the wick tube, a burner drum enclosing a portion of said burner collar and having laterally spaced inner and outer side walls cooperating to form a second passage within the inner side wall extending above the burner collar whereby the air passing

through said second passage comes in contact with the flame at a point spaced above the point of contact aforesaid.

2. In an oil burner, a wick tube having a wick associated therewith, a flame spreader having a tubular body portion arranged within the wick tube and cooperating therewith to form an annular passage for air, a baffle extending inwardly from the upper end 10 of the wick tube and projecting into the aforesaid passage for deflecting air flowing through the latter passage inwardly toward the body portion of the flame spreader prior to the discharge of said air out of the passage, an annular flange projecting laterally outwardly from the flame spreader beyond the baffle in superposed relation with the latter and cooperating therewith to form a laterally outwardly extending passage for deflecting air discharged from the aforesaid 15 passage toward the flame produced by the wick, and a cap for the flame spreader having an annular side wall located inwardly from the periphery of the flange and projecting above the latter and provided with openings therein for discharging fluid flowing through the body portion of the flame spreader outwardly above the flange aforesaid.
3. In an oil burner, a wick tube, a flame spreader having a tubular body portion arranged in the wick tube and cooperating therewith to form an annular passage for air, a circular flange extending laterally outwardly from the body portion of the flame spreader above the wick tube for deflecting air flowing through the aforesaid passage outwardly against the flame, a perforated cap for the flame spreader arranged above the flange for discharging air flowing through 20 the body portion laterally outwardly above the flange, a burner collar surrounding the wick tube and cooperating therewith to form another passage for air, said collar terminating opposite the flange whereby the air flowing through the latter passage is discharged against the flame opposite the air deflected by said flange, and still another passage for air surrounding the last-mentioned passage and projecting above the latter and terminating opposite the perforated cap aforesaid whereby the air flowing therethrough is discharged therefrom opposite the air discharged by the cap.
4. In an oil burner, a wick tube, a flame spreader having a tubular imperforate body portion arranged within the wick tube and cooperating therewith to form two separate passages for air, a baffle extending inwardly 25 from the upper end of the wick tube and projecting into the outer passage aforesaid for deflecting air flowing through the latter inwardly toward the body portion of the flame spreader prior to the discharge of said air out of the passage, a flange projecting laterally outwardly from the flame spreader beyond

the baffle in superposed relation with the latter and cooperating therewith to form a laterally outwardly extending transverse passage for directing air discharged from the inner passage aforesaid toward the flame, 70 means upon said body portion above the flange for directing air flowing through the body portion laterally outwardly above the flange, a burner collar surrounding the wick tube forming another passage for air and 75 having a portion opposite the transverse passage aforesaid for deflecting air flowing therethrough against the flame at a point opposite the air deflected by said flange, and still another passage for air encircling the 80 last-mentioned passage and terminating at a point above the flange whereby the air flowing therethrough is discharged therefrom opposite the air discharged laterally by the flame spreader. 85

5. In an oil burner, a wick tube, a flame spreader having an imperforate body portion arranged in the wick tube and cooperating therewith to form two separate inner and outer passages for air, a flange extending, 90 laterally outwardly from the body portion of the flame spreader above the wick tube and positioned for deflecting air flowing through the outer passage outwardly against the flame, a cap for the flame spreader having a 95 portion positioned above the flange and having openings in said portion through which all of the air flowing through the body portion is discharged outwardly above the flange aforesaid against the flame, a burner collar surrounding the wick tube and cooperating therewith to form a third passage for air, said collar terminating opposite the flange aforesaid for discharging air against the flame opposite the air discharged from the outer 100 passage aforesaid, and means spaced from the burner collar forming another passage for air and fashioned to prevent the air flowing therethrough from contacting with the flame until it reaches a point substantially above 105 the burner collar. 110

In testimony whereof I affix my signature.
CARROLL M. BREED.
